CLAIM

The ornamental design for a combined linear surgical stapler and cutter, as shown and described.

DESCRIPTION

FIG. 1 is a side perspective view of a combined linear surgical stapler and cutter, showing my new design; FIG. 2 is a top plan view thereof;

FIG. 3 is a rear elevational view thereof;

FIG. 4 is a side elevational view thereof;

FIG. 5 is a front elevational view thereof;

FIG. 6 is a side elevational view thereof, opposite that shown in FIG. 4; and

FIG. 7 is a bottom plan view thereof.
